FIREARM WITH RECIPROCATABLE BOLT HAVING TRANSVERSE MOVEMENT

Gary Wilhelm, Hamden, Conn. (Apt. 54, 470 Prospect St., New Haven, Conn.), and Henry Schorn, R.F.D. 1, Sandy Hook, Conn.

Filed Aug. 6, 1958, Ser. No. 753,562

9 Claims. (Cl. 42—22)

The present invention relates to firearms, and particularly to a new and improved firearm having a breech bolt action that will prevent detonation of the cartridge during loading; a trigger action that cannot accidentally be operated regardless of the treatment to which the rifle is subjected; and an automatically operating interlocking mechanism between the trigger and hammer releasing mechanism.

An object of this invention is to provide a rifle in which a cartridge in the firing chamber cannot be detonated during the action of the bolt and until the bolt is completely in battery.

Another object of this invention is to provide a rifle in which a compound motion must be applied to the trigger to effect its operation.

Another object of this invention is to provide a rifle in which the sear plate is automatically interlocked with the trigger so that it cannot be displaced by inertia in the event the rifle is dropped or subjected to sudden impact.

One aspect of the invention may be to provide a reciprocable bolt that is displaced transversely of the barrel at the beginning of the cartridge unloading operation, and which bolt remains so displaced throughout its reciprocating action. When, and only when, the bolt returns to battery, it may be transversely returned to a position aligning the firing pin with the cartridge primer. This bolt-displacing action may be accomplished by providing a reciprocable sled or action slide having cam surfaces that cooperate with mating cam surfaces on the bolt. The cooperation between these cam surfaces may initially displace the bolt transversely of the cartridge chamber at the beginning of the cartridge unloading operation, withdraw the bolt from battery to its open condition, return the bolt to battery from its open condition, and finally return the bolt to a position where its firing pin is in alignment with the primer of the cartridge that has been loaded into the firing chamber by the bolt action.

Another aspect of the invention may be to provide a trigger mechanism requiring a compound motion to operate it. This may be accomplished by employing an interference member in line with the trigger or any part movable with it, in the latter of which may be provided an interference relieving means that is normally misaligned with the interference member. An arrangement of balanced springs may be employed between the trigger and its guiding means that will require the application of a compound movement to the trigger along angularly related paths in order to align the relieving means with the interference member before the action of the trigger can be made effective.

Still another aspect of the invention may be to attach an interference member to the movable trigger mechanism that prevents movement of the sear plate until the trigger has been subjected to the compound movement required to render it effective.

The above, other objects and novel features of the invention will become apparent from the following specification and accompanying drawings which are merely exemplary.

In the drawings:

FIGURE 1 is a sectional elevational view of a portion of a rifle to which the principles of the invention

2

have been applied, and showing the bolt at the rear of its reciprocative stroke in open condition;

FIG. 2 is a view similar to FIG. 1 but with the bolt in battery ready for firing;

FIG. 3 is a view similar to FIG. 1 but showing the hammer in firing position;

FIG. 4 is a perspective view of the sled forming a portion of the bolt action;

FIG. 5 is a bottom plan view of the bolt action as viewed along line 5—5 of FIG. 1, with the trigger mechanism removed for clarity;

FIG. 6 is a perspective view of the bolt, looking at the bottom thereof and as seen in FIG. 5;

FIG. 7 is a perspective view of the sled of FIG. 4 in reversed position and as seen in FIG. 5;

FIG. 8 is a sectional elevational view of a modified form of the receiver;

FIG. 9 is a perspective view of a modified form of bolt to which the principles of the invention have been applied; and

FIG. 10 is a perspective view of a modified form of the sled shown in FIGS. 4 and 7.

Although the principles of the invention are applicable to any type of firearm including automatic, semi-automatic and manually operable, they have been shown and will be described as applied to a semi-automatic rifle, i.e., one which delivers one shot each time the trigger is pulled and which is automatically reloaded.

Referring to the drawings, and particularly to FIGS. 1, 2 and 3, a receiver or housing 10 of generally inverted channel shape may be bolted or otherwise fastened in any conventional manner to the stock of a rifle. The forward end of the receiver 10 may include a bored and threaded portion 11 for receiving the rear end of a barrel 12.

The inner side walls 13, 14 of the receiver or housing 10 may provide bearing surfaces for a reciprocable bolt 15. The bolt 15 may comprise a protuberance 16 having an upper surface that engages and slides along the inner upper surface 17 of the receiver 10. Bolt 15 may also include a conventional firing pin 18 that is normally urged rearwardly by a spring 19 within the bolt 15 in the usual manner. The bottom of the bolt 15 may include parallel, inclined recesses 20 and 21 (FIGS. 2 and 6) having cam surfaces 22, 23 and 24 formed thereby. The bolt 15 may be supported by a sled or action slide 25 (FIGS. 2, 4 and 7). The sled or action slide 25 may include openings 26 and 27 therein forming cross members 28 and 29, which latter include cam surfaces 30, 31, 32 and 33 which cooperate with cam surfaces 21, 22, 23 and 24 of the bolt 15. The sled or action slide 25 also may include bearing surfaces 34 and 35 that rest on, and slide along the top edge 36 of each of two spaced plates 37 (only one being shown), which plates receive between them the cartridge clip and trigger mechanism, all to be more fully described later. The plates 37 may be held together by pins 38 and 39, and the assembly may be received within the receiver 10.

Elongated slots 40 are provided in the side walls 13 and 14 of the receiver 10 (FIG. 3) for accommodating fingers 41, 42, 43 and 44 of a carriage mechanism 45 (FIG. 5) including plate members 45' and 46 that ride along the outer surfaces of the side walls of the receiver 10. The fingers 41, 42, 43 and 44 include surfaces 47 forming a dovetail connection with ears 48 on the sled or action slide 25. The carriage 45 is adapted to be reciprocated by any means, depending upon whether the rifle is a semi-automatic or an automatic rifle. A finger 49 may be attached to the carriage 45 for manual reciprocation thereof.

Since the carriage 45 may be reciprocated by any means, and such means per se forms no part of the pres-

ent invention, no specific means for reciprocating carriage 45 has been disclosed, except the finger 49 for manually moving the carriage 45 to its rearward position against the action of spring means which moves the carriage 45 forwardly upon release of the finger 49. Upon the firing of a cartridge, a portion of the expanding gas may be employed to act upon piston means for forcing the carriage 45 rearwardly against the action of spring means, which latter returns the carriage forwardly upon the expenditure of the force incident to the expanding gas.

The construction and arrangement of the carriage 45, sled or action slide 25 and bolt 15 are such that rearward movement of the carriage 45 causes sled or action slide 25 to move rearwardly from the position shown in FIG. 2 until cam surface 31 and 33 thereof engage cam surfaces 22 and 24 on the bolt 15, whereupon the bolt is displaced transversely of the cartridge chamber until protuberance 16 is withdrawn from an opening 50 within the receiver 10 and its top surface is at the same elevation as surface 17 thereof. Continued rearward movement of the carriage 45 moves the bolt 15 and sled or action slide 25 in nested condition to its rearmost position as shown in FIG. 1.

A cartridge clip 51 may be releasably held between plates 37 by a pivoted member 52 urged into engagement with the clip 51 by a spring 53. When the bolt 15 is at its rearmost position, a cartridge is engaged by the forward end 54 of the bolt in the usual manner, and as the carriage moves forwardly, the bullet nose 55 is directed into the rear end 56 of the barrel 12. Continued forward movement of the carriage 45, sled or action slide 25 and bolt 15 causes the cartridge to be axially aligned with the barrel 12 and to be located in the position shown in dot and dash lines in FIG. 1. In this position, the primer 57 of the cartridge is misaligned with the firing pin 18 so that should the latter inadvertently be forced forwardly during the reciprocation of the bolt 15, it would strike the cartridge rim and not the primer.

As the bolt 15 and sled or action slide 25 continue to move leftwardly (FIG. 1), the end 54 abuts against the righthand end of the barrel 12, preventing the further forward movement of the bolt. However, continued leftward movement of sled or action slide 25 may occur, which causes the cam surfaces on it and bolt 15 to force the bolt transversely of the barrel 12 so that its protuberance 16 passes into opening 50, thereby effecting the alignment of the firing pin 18 in bolt 15 with the primer of the cartridge within the barrel 12 as shown in FIG. 2.

The hammer may comprise a member 58 that may be fixed to a pin 59 oscillatably mounted in parallel side walls of a hammer housing 60 that is fixedly mounted between plates 37. Also fixed to pin 59 may be a crank arm 61 that has pinned to it two arms 62 (only one being shown). The arms 62 may be slidingly received for reciprocation within slots in a pin 63 pivotally mounted between plates 37, and a spring 64 may be located between pin 63 and a shoulder 65 on the arms 62. The hammer member 58 may include a notch 66 which, when the member 58 is moved from its position shown in FIG. 3 to its position shown in FIG. 1, engages the top portion 67 of a sear plate 68, holding the member 58 slightly below its dead center position. A wire spring 69 extends from member 58 to pin 63 for providing the initial force to move hammer member 58 across its dead center position in a counterclockwise direction, after which spring 64 and crank 61 snap the hammer member 58 upwardly into engagement with the firing pin 18.

The sear plate 68 may be mounted for reciprocation within the housing 60 or within parallel slots within side plates 37. It may include a passage 70 therethrough (FIG. 2) for the reception of the forward end 71 (FIG. 3) of a trigger mechanism 72. The sear plate 58 may be urged upwardly by a spring 73 so that its top portion 67 will always be in a position to cooperate with the

notch 66 on the hammer member 58. The spring 73 is held in proper position by a portion 74 of the spring clip 53 that holds the cartridge clip 51 in place.

The trigger mechanism 72 may include a reciprocable body member 75 that may be guided by elongated slots 76 (FIG. 2) in plates 37 and through which trunnion means 77 may extend that is rigidly fixed to the body member 75. Another pair of aligned openings 78 (only one being shown) is also arranged in plates 37 and receive other trunnion means 79 fixed to the body member 75. The openings 78, however, have provision for preventing the rearward motion of the body member 75 by the engagement between pin 79 and surfaces 80 therein. A spring 80 mounted on pin 77 normally urges the trunnion means downwardly into cooperation with the surface 80 in a balanced manner so that normal squeezing of the trigger 81 will cause the trunnion 79 to move up over surface 80, yet any other force inadvertently applied to the trigger 81 will prevent rearward movement of the body member 75. The body member 75 to which the trigger 81 is fixed includes a notch 82 therein which is normally misaligned with the lower end of a safety abutment 83 (FIG. 3) that is pivoted on a pin 84 and which abutment is urged in a counterclockwise direction by a spring 83' to cause the upper end 85 to abut the pin 39. Should the body member 75 be moved rearwardly by any action other than the action involved in squeezing a trigger, the trunnion means 79 engages the surface 80 and slot 82 is misaligned with abutment 83 (FIG. 3). However, when the trigger 81 is squeezed during firing of the rifle, surfaces 80 of openings 78 force trunnion means 79 upwardly to the position shown in FIG. 3 so that slot 82 aligns with abutment 83 and permits rearward movement of the trigger body 75. In order to additionally prevent accidental movement of the trigger 81 upwardly, the lower end of abutment member 83 may be provided with an inclined cam surface 83'' that is aligned with a mating cam surface 83''' on the trigger 81 just above the notch 82. This arrangement urges the notch 82 farther out of alignment with the bottom end of the abutment 83 when the trigger 81 is moved rearwardly by any force other than the normal squeezing force applied by a user when on range.

The forward end 71 of the body 75 may be bifurcated, forming two legs, and an oscillatable cam 86 may be mounted on a pin 87 extending between the two legs of the bifurcated end. The cam 86 may include a portion 88 (FIG. 3) for cooperation with a cam surface 89 on the lower wall of the opening 70 that passes through the sear plate 68. The construction may be such that a pin 90 extending across the legs of the bifurcated end 71 prevents movement of cam 86 in a clockwise direction when the trigger body 75 is moved rearwardly so that the portion 88 of cam 86 acts on cam 89 to force sear plate 68 downwardly to thereby release the hammer 58. The cam 86 is permitted to turn in a counterclockwise direction against a spring 91 mounted between the legs of the bifurcated end 71.

In order to prevent the sear plate 68 from being jarred downwardly accidentally, which would cause release of the hammer 58, an additional interlock is provided. It may include a plate 92 (FIG. 2) mounted on the trunnion means 77 and having an extension 93 that slidingly engages a mating groove 94 within the side of the sear plate 68. Accordingly, this extension 93 prevents sear plate 68 from being moved downwardly until the extension 93 has been withdrawn from the groove 94, at which time the portion 88 on cam 86 acts on cam 89 to force the sear plate downwardly, thereby releasing the hammer 58.

When the hammer 58 actuates the firing pin 18, it detonates the primer of a cartridge in the barrel 12. The force generated by the exploding shell, or any other force such as a manual force, may be employed in a known manner to force carriage 45 rearwardly, and with it sled

25, which action may store up energy in spring means or the like for returning the carriage 45 and bolt 15 to battery after it has ejected the exploded cartridge case, all as is well known in the art. The rearward movement of sled or action slide 25, as previously explained, initially acts to cause cam surfaces 31 and 33 (FIG. 2) to engage cam surfaces 22 and 24, thereby moving bolt 15 transversely relatively to the barrel 12 so that protuberance 16 is withdrawn from opening 50. Continued rightward movement of the sled or action slide 25 and bolt 15 in nested condition forces the hammer 58 in a clockwise direction until its notch 66 is engaged by the top portion of the sear plate 68, cocking the hammer. It is to be noted that an additional safety feature is provided in the formation of the righthand end of the sled or action slide 25 which includes an upturned portion 95 that prevents the hammer 58 from striking the firing pin during the entire reciprocative stroke of the bolt 15 and while the bolt 15 and sled or action slide are in nested condition. When the bolt is in battery, however, the portion 95 exposes the firing pin 18, as shown in FIG. 2.

Referring to FIGS. 8, 9 and 10, the principles of the invention are shown as applied to a modified structure including a receiver 100 having a threaded portion 101 to receive a barrel similar to the barrel 12. The receiver 100 is adapted to receive a sled or action slide 102 between its side walls which are made up of opposed wall or side plates 103 (only one being shown). The walls 103 may include cam paths 104 and 105 which receive cams 106 and 107 on each side of a bolt 108. The bolt 108 may include protuberances 109 and 110 that are adapted to be received within recesses 111 and 112 in receiver 100 when the bolt 108 is in battery.

The sled or action slide 102 and bolt 109 are adapted to lie within the chamber 110 formed within the receiver 100, and the plate members 45' and 46 (FIG. 5) are adapted to engage the ends of walls 103 in a similar way to the way these members engage ears 47 and 48 of sled 25. Reciprocation of the carriage 45 will, therefore, cause reciprocation of sled or action slide 102, and the cooperation of the cams 104, 105 with the cams 106 and 107 will effect transverse movement of the bolt 108 into and out of battery in a manner to prevent alignment of the firing pin 111 with the primer of a cartridge within the barrel except when the bolt is locked in battery.

The side walls 103 may be provided with aligned holes 112' and 113' that receive discs 114 and 115. These discs may have slots in them for receiving ears 116 and 117 of a base member 118 that extends between the walls 103. In assembled relation, the base 118 rests on top of the top cartridge within the clip 51 and prevents the bolt 108 from striking the top cartridge with an impact each time the bolt is moved transversely from battery during a reciprocative stroke thereof.

Although the various features of the new and improved firearm have been described in detail to fully disclose two embodiments of the invention, it will be evident that changes may be made in such details and certain features may be used without others without departing from the principles of the invention.

What is claimed is:

1. In a gun, a receiver; a barrel fixed to said receiver; a reciprocable unitary bolt within said receiver and having a firing pin axially disposed therein; an action slide for supporting said bolt; a reciprocable carriage connected to said slide; and cam means between said slide and bolt for moving said bolt and firing pin transversely of said barrel while maintaining them in parallel relation thereto during each reciprocation of said bolt.

2. In a gun, a receiver; a barrel fixed to said receiver; a reciprocable unitary bolt within said receiver and having a firing pin axially disposed therein; an action slide for supporting said bolt; a reciprocable carriage connected to said slide; and cam means between said slide and bolt for moving said bolt and firing pin both axial-

ly and transversely of said barrel while maintaining them in parallel relation thereto during each reciprocation of said bolt.

3. In a gun, a receiver; a barrel fixed to said receiver; a reciprocable unitary bolt within said receiver and having a firing pin axially disposed therein; an action slide for supporting said bolt; a reciprocable carriage connected to said slide; cam means between said slide and bolt for moving said bolt and firing pin transversely of said barrel while maintaining them in parallel relation thereto during each reciprocation of said bolt; and means on said slide for preventing said firing pin from being actuated during a substantial portion of the reciprocative stroke of said bolt.

15 4. In a gun, a receiver; a barrel fixed to said receiver; a unitary bolt; a firing pin axially disposed within said bolt; means for supporting said bolt and mounted within said receiver, said means comprising a pair of side plates joined by a bottom member; cam means on said side plates; cam means on the sides of said bolt for cooperation with the cam means on said side plates to effect the movement of said bolt and firing pin axially and transversely relatively to said barrel when said bolt supporting means is reciprocated; and means for reciprocating said bolt supporting means.

20 5. In a gun, a receiver; a barrel fixed to said receiver; a unitary bolt; a firing pin axially disposed within said bolt; means for supporting said bolt and mounted within said receiver, said means comprising a pair of side plates; aligned opposed means in each plate adapted adjustably to receive means on another plate forming a bottom for said bolt supporting means; cam means on the sides of said side plates; cam means on the sides of said bolt for cooperation with the cam means on said side plates to effect the movement of said bolt and firing pin axially and transversely relatively to said barrel when said bolt supporting means is reciprocated; and means for reciprocating said bolt supporting means.

25 6. In a gun, a receiver having a chamber therein; a barrel fixed to said receiver; a bolt-supporting action slide within said chamber and including a generally channel-shaped member having cam means on opposed side walls thereof; means for reciprocating said action slide; and a unitary bolt having a firing pin axially disposed therein supported by said action slide and including cam means on opposed sides thereof for cooperation with the cam means on said action slide side walls, said cam means, during the initial and final movements of said slide action, causing movement of said bolt and firing pin transversely of said barrel while maintaining said bolt parallel to said barrel at all times, and the intermediate movement of said slide action causing unitary movement of said action slide and bolt.

30 7. In a gun, a receiver; a barrel fixed to said receiver; a bolt mounted within said receiver; an action slide within said receiver; a reciprocable carriage connected to said action slide; spaced, identical cam means along said bolt; spaced, mating cam means along said action slide; and means for reciprocating said action slide to cause all of 35 said cam means to mutually cooperate to move said bolt axially and transversely of said barrel while remaining in parallel relation thereto at all times.

35 8. In a gun, a receiver; a barrel fixed to said receiver; a unitary bolt mounted within said receiver; a firing pin axially disposed within said unitary bolt; a reciprocable carriage; an action slide connected to said carriage and located within said receiver; and means for causing said bolt and said firing pin to be moved axially and transversely of said barrel while remaining in parallel relation to said barrel at all times, said means comprising mating cam means between said bolt and action slide that nests during a portion of the reciprocation of said carriage and acts to apply equal transverse motion to all points along said bolt during other portions of the reciprocation of said carriage.

9. In a gun, a receiver; a barrel fixed to said receiver; a bolt mounted within said receiver; an action slide within said receiver; a reciprocable carriage connected to said action slide; spaced, identical cam means along the bottom of said bolt; spaced, mating cam means along the top of said action slide; and means for reciprocating said action slide to cause all of said cam means to mutually cooperate to move said bolt axially and transversely of said barrel while remaining in parallel relation thereto at all times.
